UNITED STATES PATENT OFFICE.

CHARLES RYDER, OF BRIDGEPORT, CONNECTICUT, ASSIGNOR TO WOLVERINE MOTOR WORKS, INC., OF BRIDGEPORT, CONNECTICUT, A CORPORATION OF MICHIGAN.

METHOD OF OPERATING OIL ENGINES AND IMPROVED OIL ENGINES.

Application filed October 21, 1921. Serial No. 509,245.

My invention relates to a new and improved internal combustion engine.

One of the objects of my invention is to devise a new and improved internal combustion engine which will be particularly adapted for burning heavy oils.

Another object of my invention is to devise an internal combustion engine in which the fuel and air of combustion will be violently agitated before and also during the period of combustion so that maximum fuel efficiency will be produced and carbon deposits will be minimized.

Another object of my invention is to devise an internal combustion engine which will be extremely flexible, even when heavy oils are used for the fuel, so that the engine will operate uniformly and in a reliable manner when it is revolving very slowly under minimum load and when it is revolving rapidly under maximum load.

Another object of my invention is to devise an engine which will be adapted for use with a large variety of fuels and in which relatively heavy oils can be used with a compression much lower than the compression of a Diesel engine.

Other objects of my invention will be set forth in the following description and drawings which illustrate a preferred embodiment thereof.

Fig. 1 is a sectional view partly in elevation of the cylinder head of the engine and of the specially shaped piston thereof, the piston being shown at the end of the compression stroke.

Fig. 2 shows an indicator graph illustrating the operation of the said engine. The scale of the spring is 200 lbs. per inch.

In the preferred embodiment illustrated, the engine is of the four cycle type. The cylinder 1 can be constructed in the ordinary manner and it is provided with a cylinder head 2, which is suitably secured thereto in any well known manner. The cylinder head 2 has a projection 31 of substantially cylindrical form which is spaced from the annular wall of the cylinder and extends into the cylinder. The cylinder and the cylinder head are provided with a water jacket 4 so that both are kept cool. The cylinder head 5 has in the center thereof an inlet valve 5 mounted at the end of the spindle 6. This valve 5 is the air inlet valve. The spindle 6 is provided with a head 7 and it is sur-

rounded by a compression spring 18 which tightly closes the valve 5. The head 7 is provided with a contact member 8, which co-operates with the end of the pivoted lever 9. This pivoted lever 9 is pivoted at 10 and it can be suitably controlled in the well known manner by means of a cam or the like. I have not illustrated these well known details because they are well known to the art and in themselves they form no part of my invention. The pump inlet 14 is located at one side of the inlet valve 5. The pump itself is mounted in the recess 15 of the cylinder head. The pump may be of any ordinary and well known type and it is adapted to drive the oil into the combustion chamber with great force, under a pressure which is preferably as high as 1,000 lbs. per square inch. The piston or plunger of the pump is sprayed in any well known manner by means of a cam, eccentric or the like as is well known in the art. At the other side of the inlet valve 5, the exhaust passage 15 is located and this is controlled by the valve 7', having a piston part 19 which fits tightly in the recess in which it is mounted. The valve 7' is mounted upon the stem 20 provided with a head 21 and the compression spring 22 keeps the exhaust valve 7' tightly closed. The valve 20 can be depressed by means of the pivoted lever 24, controlled by rod 11, pivoted thereto at 12.

The piston 26 is provided with the usual piston rings 27, and at the top thereof it is provided with the usual piston rings 27 and it is also provided at the top thereof with a recess 28 having substantially vertical and cylindrical side walls which are adapted to substantially close the annular space between the exterior of the projection 31 and the interior wall of the cylinder.

I prefer to leave a clearance of about $\frac{1}{16}$ th of an inch between the annular upper part of the piston 26 and the projection 31. 100

The operation of my invention is as follows:

On the first or suction stroke of the piston the valve 5 opens and the fresh air is drawn in in the ordinary and well known manner. On the compression stroke of the engine the pump is operated and the oil is forced in, in the form of very fine drops and under great pressure. I prefer not to cause the oil to be forced in until the annular top 110

of the piston 26 has passed above the bottom of the projection 31. As can be seen from the graph in Fig. 2, I prefer not to force in the fuel until very near the end of the 5 compression stroke. I prefer to have the annular top of the piston pass above the bottom of the projection 31 when the crank to which the said piston is connected is inclined about 40° to the vertical. It is 10 obvious that the air in the annular compression space between the projection 31 and the wall of the cylinder will be more highly compressed than the air in the combustion chamber, as the piston 26 continues 15 to the end of the compression stroke.

Hence, the air will be forced into the combustion chamber under considerable pressure through the narrow clearance between the projection 31 and the annular top of the 20 piston and this air will enter in the form of a strong narrow annular blast which will spread out inwardly, this effect being assisted by the curved contour of the base of the recess in the piston. In addition, since the 25 entering blast of compressed air impinges upon the piston which is moving in the opposite direction, the agitating effect in the combustion chamber will be increased so that a very powerful agitation is produced. 30 It will be noted that the oil inlet 14 is inclined to the axis of the cylinder and to the adjacent part of the head of the piston so that the drops of oil tend to travel to the right and to meet the blast of air coming from the right hand side of the compression chamber. It is believed that the 35 annular current of air spreads inwardly along the piston head until the center of the piston head is reached and the said 40 current of air then ascends so that the air in the combustion chamber is powerfully agitated in closed paths while the oil is being injected.

As the relative dimensions of the parts 45 are important in order to secure the results before mentioned, the drawing has been made according to scale and from an actual working engine and whose dimensions are as follows:

50 The diameter of the projection 31 is $6\frac{3}{8}$ inches; the interior diameter of the adjacent annular portion of the piston is $6\frac{1}{4}$ inches and the exterior diameter of the piston is $8\frac{1}{4}$ inches. The distance between the 55 bottom of the recess in the piston and the projection 31 is $1\frac{5}{8}$ inches and the height of the projection 31 is $1\frac{3}{4}$ inches. The piston stroke is 11 inches.

60 The projection 31 may be shortened to about $\frac{7}{8}$ inch but it is desirable not to make said projection too long. The annular piston projection becomes intensely hot because it is a relatively narrow ring. This 65 annular projection cannot be cooled by a piston water jacket and the heat in the nar-

row piston top cannot be efficiently conducted to the broad base of the piston because the piston top is only about an inch thick. Hence the only cooling effect on the piston top is that exerted by the adjacent 70 cylinder wall, which is cooled by the water jacket 4. The piston rings at the top of the piston are useful because they make positive contact with the cooled cylinder wall and thus conduct the heat of the piston thereto. 75 However, if the annular piston end is made too long, the temperature thereof rises to such an extent, and the piston rings expand so much, that the piston rings tend to stick in the cylinder, thus causing loss of power 80 and other serious disadvantages.

The engine is preferably operated at about 350 revolutions per minute under normal load and at a compression of about 350 lbs. per square inch. Of course, the compression depends upon the type of fuel used. 85

The indicator graph shows that the ignition of the fuel is substantially an explosion which may take place as the fuel is injected, shortly before the compression stroke is completed. When the fuel is injected, preferably without the use of air, into the compressed and rapidly agitated air in the combustion chamber, it is believed that the lighter constituents of the fuel ignite immediately, causing a very rapid combustion 90 of the heavy constituents of the fuel. 95

I have described a preferred embodiment of my invention, but it is clear that numerous changes and omissions could be made 100 without departing from its spirit.

What I claim is:

1. An internal combustion engine having a substantially cylindrical projection in the head of the cylinder thereof, said engine 105 having a piston provided with a recess into which said cylinder projection can enter, the top of the piston being of substantially annular shape and being adapted to enter the annular cylinder space between the wall of 110 the cylinder and the annular projection thereof, the parts being so dimensioned that when the said piston is moved inwardly upon its compression stroke the air in said annular cylinder space is compressed to a higher pressure than the air located in the recess of the piston, said recess constituting a combustion chamber into which a powerful annular current of air is forced from 115 said annular cylinder space during a portion of the inner stroke of the piston, said combustion chamber having a fuel inlet communicating directly therewith and having an air inlet therein.

2. An oil engine having a cylinder provided with an inward projection in the head thereof forming a portion of the wall of the combustion chamber, said projection being spaced from the cylinder wall to form 125 a compression space intermediate said pro- 130

- jection and the cylinder wall, said combustion chamber having fuel and air inlets communicating therewith, the piston having an end part adapted to fit closely but with 5 a clearance against a corresponding portion of said projection and to enter said compression space before the end of the compression stroke, whereby air is forced from said compression space at the end of the 10 compression stroke between the closely fitting corresponding portions of said projection and of said piston end part, said piston end part having a piston ring adapted to enter said compression space at the end of the 15 stroke and to pass above the bottom of the said corresponding portion of said projection.
3. An internal combustion engine having a cylinder provided with an inward projection in the head thereof forming part of 20 the wall of the combustion chamber, said projection being spaced from the cylinder wall to form a compression space, said combustion chamber having fuel and air inlets 25 communicating therewith, the piston having a recessed annular end adapted to enter said compression space to force air continuously therefrom into said combustion chamber, the height of said projection being less than 30 substantially twenty-two percent (22%) of the interior diameter of the cylinder, the inner wall of said annular end having a clearance with respect to the projection of
- said cylinder so that the air intermediate 35 said projection and the cylinder wall can be forced through said clearance into the recessed end of the piston at the end of the compression stroke.
4. An oil engine having a substantially 40 cylindrical projection in the head thereof, said engine having a piston provided with an annular end the base of which is of concave contour forming a recess in said piston, the annular end of said piston being adapted 45 to enter the annular cylinder space between the wall of the cylinder and the annular projection thereof, said cylinder head having an oil inlet therein inclined to the axis of movement of the piston, the parts being so dimensioned that when the said piston is moved 50 inwardly upon its compression stroke, the air in said annular cylinder space is compressed to a higher pressure than the air located in the piston, said recess constituting 55 a combustion chamber into which a powerful annular current of air is forced from said annular cylinder space during a portion of the inner stroke of the piston, said annular current of air being deflected by the concave end of said piston space to 60 the center of the piston, whereby the inclined jet of oil is forced into a violently agitated body of air.

In testimony whereof I hereunto affix my signature.

CHARLES RYDER.
